FOREIGN PATENT DOCUMENTS

EP 2239104 A1 10/2010

Primary Examiner — Philip S Hyder(74) *Attorney, Agent, or Firm* — Jacob M. Ward; Ward Law Office LLC(57) **CLAIM**

The ornamental design for a hand tool with flange, as shown and described.

DESCRIPTION

FIG. 1 is a top perspective view of a hand tool with a flange; FIG. 2 is a top plan view of the hand tool shown in FIG. 1; FIG. 3 is a top plan, exploded view thereof; FIG. 4 is a left-side elevational view thereof; FIG. 5 is a rear elevational view thereof; and, FIG. 6 is a front elevational view thereof.

The ornamental design which is claimed is shown in solid lines in the drawings. The broken lines in the drawings form no part of the claimed design. A bottom plan view is not shown because it is identical to the top plan view shown in FIG. 2. A right-side elevational view is not shown because it is a mirror image to the left-side elevational view shown in FIG. 4.
